ABSTRACT OF THE DISCLOSURE

Holder for keys consisting of a case open at one side, with one or more plates freely slidably into and out of said case, but releasably confined against separation from the case and provided on one or both sides with spring key holding clips and with a flange or flanges along the outer edge or edges for closing the open side of the case.

The general objects of this invention are to provide a light, small, compact form of key holder of a size to be carried in the pocket or pocketbook and in which a number of keys may be securely held in fully observable, readily removable relation.

The drawing accompanying and forming part of this specification illustrates present practical embodiments of the invention.

Structure, however, may be modified and changed as regards the immediate illustration; all within the true intent and scope of the invention.

FIG. 1 is a front elevation of one of the new keyholders, with a slide on which keys are mounted, withdrawn from the case, for extraction of keys retained thereon.

FIG. 2 is an edge view of the case in closed condition.

FIG. 3 is an edge view, half shown in vertical section as on line 3—3 of FIG. 1.

FIG. 4 is a plan of one of the key holding slides removed from the case.

FIG. 5 is an enlarged cross sectional detail as on line 5—5 of FIG. 4.

FIG. 6 is a front view showing one of the key carrying plates partly removed from the case.

FIGS. 7 and 8 are perspective and plan views of a modified form of the invention.

The case, indicated generally at 7, may be of light, thin material, such as sheet metal or plastic, of rectangular formation, open along one side at 8 and in this case having an intermediate partition wall 9 providing separate key chambers 10 and 11.

The key carrying plates are numbered 12 and 13, disposed in compartments 10 and 11, at opposite sides of the separating partition 9.

These plates may be duplicates having flanges 14 on their outer edges, meeting at the center to form a complete closure for the open side of the case.

The inner edges of the keyplates carry guide strips 15, FIG. 4, of a length to slidably fit in the case and having angled ends 16 acting as hooks to engage stop pins 17 in the outer edge portions of the case.

Upon angling the key plate in respect to the case, the hooked ends of the plate may be disengaged from the holding pins 17, as will be clear in FIG. 6.

The keys are releasably retained on the supporting plates in keyholding pockets made up of overlying strips 18 in spaced parallel relation on the plates having inclined abrupt holding edges 19 for guiding the edges of the keys and light strip springs 20 for gripping the opposite edges of the keys.

These spring holders firmly secure the keys on the mounting plates but permit the keys to be readily separated from the plates.

2

It will be noted that the supporting plates 12 are of a width less than the overall length of the keys leaving the heads 21 of the keys fully exposed to be readily gripped between opposed fingers of a hand.

As shown in FIG. 1, the holder is ordinarily used by simply withdrawing the slide carrying the desired key; the hooked ends of the guide 15 then retaining the slide in position for easy removal of the desired key.

If, however, the key carrying member is to be entirely removed from the case, this can be easily effected by simply turning the slide at an angle to the case, as in FIG. 6, to separate first one and then the other of the end hooks from the stop pins 17.

All parts of the holder may be of small size and of light sheet material so that the holder may be of light weight convenient for carrying and use.

Each slide is shown as carrying two keys on opposite sides of the same, but more or a less number of keys may be mounted on the slides.

The frictional engagement of the slides in the case may ordinarily be sufficient to keep the slides properly confined in the case, but special means such as tab extensions 22 on the flanges 14 may be provided for yielding holding engagement with the confining walls of the case.

The springs 20 hold the keys against rattling or looseness on the supporting plates.

These may be of light strip spring material wrapped about a portion of the pocket forming strip 18 at one end at 23 and extending from the supported end into the key receiving space of the pocket.

The bars 15 at the inner edges of the plates act as guides in free sliding engagement in the case and serve as retainers to prevent separation of the plates from the case, unless such separation may be intended, as for the removal or replacement of individual keys.

The holder keeps a group of keys such as ordinarily required, in orderly easily recognized relation, fully covered and protected but instantly available, and readily removable and replaceable.

The cover forming flanges 14 provide convenient finger grips for sliding the key supports into and out of the case and for manipulating into the inclined positions necessary to remove the supports from the case.

FIGS. 7 and 8 show how the invention may be made up with a single slide 23, carrying integrally cut out key holding strips 24.

The means for retaining the slide in the case is shown as a rod or bar 25 on the inner edge of the slide plate having its ends bent into hook forming loops 26, engageable around pins 27, in back of the case to hold the slide in retracted position.

These hooks 26 also are engageable about the pins 28 in the front of the case to limit the extracting movement of the slide and prevent accidental removal of the slide.

Intentional removal of the slide may be effected by rocking the same into an angular relation, as previously described and shown in FIG. 6.

The guide bar 25 at the inner edge of the slide plate may be relatively rigid, but with the hook members 26 extended at opposite ends of the bar resilient to snap about the holding pins 27. This bar with the hooked ends may be a single piece of spring material, substantially as indicated, with the hook parts resilient to snap into and out of engagement with pins 27 and 28 and the intermediate portion below the hooks substantially rigid to assure proper spring hinging action of the hooks.

What is claimed is:

1. A keyholder comprising a case open along one side and provided with stop pins at opposite ends of said open side,

a key carrying plate insertable into and removable through said open side of the case,

a guide rod at the inner edge of said plate of a length substantially equal to the length of said open side and having hooked ends engageable with said stop pins,

key holding pockets on said plate and a flange on the outer edge of said plate forming a closure for said open side of the case.

2. The invention according to claim 1 with two of said key holding plates disposed in back-to-back relation in said case with opposed flanges forming a closure for the open side of the case.

3. The invention according to claim 1 with springs in said key holding pockets disposed for yielding holding engagement with the edges of the keys inserted in said pockets.

4. A keyholder comprising

a case,
a supporting plate slideable into and out of said case, said plate having a width less than the length of a normal key so as to leave the head of a key on the 20 plate exposed at both sides for gripping between the fingers,

a key pocket forming strip spaced the approximate thickness of a key over said plate,

a light key engaging spring extending into said pocket 25 for yieldingly retaining a key inserted into said pocket,

a finger grip flange at the outer edge of said plate,

a guide bar at the inner edge of the plate slidably cooperable with inner walls of the case, said guide bar having hooked ends and the case having stops engageable by said hooked ends to prevent accidental separation of the plate from the case, but permitting removal of the plate when inclined in respect to the case.

5. A keyholder comprising

a case,
a supporting plate slideable into and out of said case, a key pocket forming strip struck out of said plate and spaced the approximate thickness of a key over said plate,

the guide bar at the inner edge of said plate having hooked ends slidably engageable with the inner walls of the case, and
abutment forming pins in the case engageable by said hooked ends of said bar.
